US0D1108402S

(12) **United States Design Patent** (10) **Patent No.:** **US D1,108,402 S**
(45) **Date of Patent:** **** Jan. 6, 2026**

(54) **EARPHONE**

(71) Applicant: **Audio-Technica Corporation**, Tokyo (JP)

(72) Inventors: **Yosuke Takubo**, Tokyo (JP); **Yutaro Kumagai**, Kanagawa (JP); **Yuki Nogiri**, Kanagawa (JP)

(73) Assignee: **Audio-Technica Corporation**, Tokyo (JP)

(**) Term: **15 Years**

(21) Appl. No.: **29/956,146**

(22) Filed: **Aug. 6, 2024**

(30) **Foreign Application Priority Data**

Feb. 29, 2024 (JP) ..... 2024-004154 D
(51) **LOC (15) Cl.** **14-01**
(52) **U.S. Cl.**
USPC **D14/223**
(58) **Field of Classification Search**
USPC D14/205, 206, 223, 202
CPC H04R 1/10; H04R 1/1016; H04R 1/2842

(57) **CLAIM**

The ornamental design for an earphone, as shown and described.

DESCRIPTION

FIG. 1 is a front, top, right side perspective view of an earphone, showing our new design;
FIG. 2 is a rear, top, left side perspective view thereof;
FIG. 3 is a front view thereof;
FIG. 4 is a rear view thereof;
FIG. 5 is a top plan view thereof;
FIG. 6 is a bottom plan view thereof;
FIG. 7 is a left side view thereof; and,
FIG. 8 is a right side view thereof.
Evenly broken lines depict portions of the earphone which form no part of the claimed design.

1 Claim, 8 Drawing Sheets
